HACK SAW

Raymond C. Dreier, Chicago, Ill., assignor to Dreier Brothers, Inc., Chicago, Ill., a corporation of Illinois

Application January 19, 1955, Serial No. 34,059

Term of patent 14 years

(Cl. D93—3)

FIG. 1

FIG. 2

FIG. 3

FIG. 4

Fig. 1 is a plan view of a hack saw embodying my new design;

Fig. 2 is a bottom view thereof;

Fig. 3 is an end view of the hack saw as seen from the left of Fig. 1; and

Fig. 4 is an end view of the hack saw as seen from the right of Fig. 1.

I claim:

The ornamental design for a hack saw, substantially as shown.
